UNITED STATES PATENT OFFICE.

SAMUEL KAYE, OF COLUMBUS, MISSISSIPPI.

DESIGN FOR A CROWN CORK OR SEAL FOR CAPPING BOTTLES.

48,033.

Specification for Design.

Patented Oct. 26, 1915.

Application filed August 18, 1914. Serial No. 857,416. Term of patent 14 years.

To all whom it may concern:

Be it known that I, SAMUEL KAYE, a citizen of the United States, residing at Columbus, in the county of Lowndes and State of Mississippi, have invented a new, original, and ornamental Design for Crown Corks or Seals for Capping Bottles, of which the following is a specification, reference being had to the accompanying drawing, forming part thereof, in which—

Figure 1 is a perspective view; Fig. 2

is a top view; and Fig. 3 is a bottom view of a crown cork or seal illustrating my new design.

I claim:—

The ornamental design for a crown cork or seal for capping a bottle, as shown.

SAMUEL KAYE.
